[57] **CLAIM**

The ornamental design for a blanket with dual thermal characteristics, as shown and described.

DESCRIPTION

FIG. 1 is a perspective view of a blanket with dual thermal characteristics showing my new design; FIG. 2 is a front elevational view thereof; FIG. 3 is a rear elevational view thereof; FIG. 4 is a right side elevational view thereof; FIG. 5 is a left side elevational view thereof; and, FIG. 6 is a top plan view thereof, the bottom view being a mirror image of the top view shown in FIG. 6. The criss-cross pattern, which represents fabric, fragmentarily shown in FIGS. 1 and 6, is understood to extend throughout each of the two panels.

FIG.1

FIG. 2

FIG. 3

FIG. 4

FIG. 5

FIG. 6
